PLUG AND RECEPTACLE SWITCH

William H. Frank, Detroit, Mich.

Application July 30, 1937, Serial No. 156,439

3 Claims. (Cl. 200—114)

This application relates to plug and receptacle switches.

A principal object of the invention is to provide a plug and receptacle switch which is extremely compact and inexpensive of manufacture and extensive of operation, these results being obtained by a novel arrangement of parts.

Further objects will best be understood on reference to the drawings disclosing the switch.

In these drawings,

Fig. 1 shows the switch in front elevation, with the plug thereof partially cut away.

Figs. 2 and 3 are sections on lines 2—2, 3—3, Fig. 1.

Figs. 4, 5, and 6 illustrate the cooperation of the parts for switching.

The switch herein illustrated is of the two-pole type and comprises a cup shaped body 10 adapted to receive a twin plug or head 11. The body is shown as if mounted on a vertical wall.

The twin plug 11 comprises a front 12, a top 14, and a central barrier 16 projecting rearwardly from the front. The top is divided by the front so that it is divided into two parts, one a blade 18 or plate part 18 and the other a handle part 17 containing finger grip holes 19. Ledges 18 connect handle part 17 to front part 12 to reinforce the plug. All of the plug parts 12—17 are preferably integral and are shown as formed of a single piece of insulating material.

Within the receptacle body, and near the top thereof are pairs of contacts 20 connected by binding posts 21 to external conductors. In the back wall of the body are openings 22, certain of which are near the contacts 20 and others of which are remote from the contacts 20. On opposite surfaces of the plug blade 18, and for engaging the pairs of stationary contacts 20 there are provided pairs of contacts 24. On one surface of the plug blade 18 are mounted plug fuse socket shells 27; rivets 28 whose heads are within the shells and form the center contacts of the latter, are electrically connected to certain of the contacts 24; the shells 27 are electrically connected to the other contacts 24; thus contacts 20 may be interconnected through contacts 24, rivets 28, and plug fuses 30 within the shells 27. The rivets 28 hold the parts together.

When the plug is plugged into the cup (Figs. 1, 2, 3, 4, and 5) the plug front 12 forms a closure for the open front of the cup and covers all of the parts within the cup, and thus debars access to the live parts within the cup.

In order to guide the plug as it is plugged into the cup, in the "on" position of Figs. 3 and 4, or

the "off" position of Fig. 5, there are provided, in the side walls of the cup four slots 35 with pairs thereof designed to receive side edges of the plug blade 18. When the plug is plugged into the cup, as in Figs. 3 and 4, the side edges of the blade ride in the slots 35 nearer the contacts 20 and the parts assume the position of Fig. 3, with the blade end in the back wall openings 22, and with contacts 20 engaged by contacts 24. On the other hand when the plug is to be inserted into the cup in the "off" position of Fig. 5, the plug is reversed 180° from the position of Figs. 3 and 4 to the position of Fig. 5 and plugged in; the side edges of the blade then ride in the slots 35 at the end of the cup more remote from the contacts 20, and the blade end fits into others of the back wall openings 22; contacts 20 are not engaged by the contacts 24 and consequently a circuit through the switch is not established.

It will be observed that contacts 20 are protected from accidental contact, when the plug is removed and the front of the receptacle is open, by the formations at 40, integral with the receptacle, and through a slot 41 of which rides the blade 18 and the contacts 24.

The extended or rear end 42 of the blade, as extended beyond the contacts 24, cooperates with the walls of slot 41 to provide an arc snuffing means for the contacts.

I claim:

1. In a switch, a block of insulation having a deep slot opening therewith from the front thereof, adjacent contacts in said block on opposite sides of said slot, a blade adapted to slide in said slot and having on opposite sides contacts for engaging the block contacts, a fuse carried by said blade and connecting the blade contacts.

2. In a switch, a receptacle comprising a cup shaped body having a deep slot opening therewith from the bottom of the cup depression in the body, adjacent contacts in said body on opposite sides of said slot, a blade adapted to slide in said slot and having on its opposite sides contacts which engage the body contacts when the blade is in the slot in "on" position and which do not otherwise engage the body contacts, the blade being formed as part of a plug having a closure portion transverse to the blade and defining a closure for the cup depression of the body when the blade is in the slot, the blade contacts being behind the plug closure portion, and the body contacts being behind the plug closure portion

so that when the blade is in the slot all contacts are concealed and inaccessible, the plug carrying behind the plug closure portion a fuse receiver

in which is a fuse bridging the blade contacts, the plug having a handle in front of the plug closure portion.

3. In a switch, a receptacle comprising a cup shaped body having a deep slot opening therewith from the bottom of the cup depression in the body, adjacent contacts in said body on opposite sides of said slot, a blade adapted to slide in said slot and having on its opposite sides contacts which engage the body contacts when the blade is in the slot in "on" position and which do not otherwise engage the body contacts, the blade being formed as part of a plug having a closure portion transverse to the blade and defining a closure for the cup depression of the body when the blade is in the slot, the blade contacts

being behind the plug closure portion, and the body contacts being behind the plug closure portion so that when the blade is in the slot all contacts are concealed and inaccessible, the plug carrying behind the plug closure portion a fuse receiver in which is a fuse bridging the blade contacts, the plug having a handle in front of the plug closure portion, the slot being at one end of the cup depression, and the plug and body parts being so designed that the plug may 10 be plugged into the cup depression in either one of two reverse positions, with the blade at an end of the cup depression, near or remote from the slot. 5

WILLIAM H. FRANK. 15
